CLAIM

The ornamental design for a single row seven day pill box, as shown and described.

DESCRIPTION

FIG. 1 is a top and front perspective view of a single row seven day pill box showing our new design;

FIG. 2 is a front view thereof;

FIG. 3 is a rear view thereof;

FIG. 4 is a left side view (viewer's perspective) thereof;

FIG. 5 is a right side view (viewer's perspective) thereof;

FIG. 6 is a top view thereof; and,

FIG. 7 is a bottom view thereof.

It is noted that any broken line illustration of environmental structure in the drawings is not part of the design sought to be patented.
